DESIGN FOR A DRESS

Edna Breer, New York, N. Y.

Application February 15, 1941, Serial No. 99,029

Term of patent 3½ years

To all whom it may concern:

Be it known that I, Edna Breer, a citizen of the United States and a resident of the city of New York, in the county of New York and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress as shown in Fig. 1.

The characteristic feature of my design resides in the combination on the dress disclosed of the specific loop trimming around the shoulder yokes and back of neck in association with the matching trimming around the sleeves, as shown.

I claim:

The ornamental design for a dress, substantially as shown and described.

EDNA BREER.
